US00D987724S

(12) United States Design Patent (10) Patent No.: US D987,724 S
(45) Date of Patent: * May 30, 2023

(54) VIDEO GAME CONTROLLER

(71) Applicant: Cyber Gadget Holdings Corporation,
Tokyo (JP)

(72) Inventor: Takeo Yamaguchi, Tokyo (JP)

(73) Assignee: CYBER GADGET HOLDINGS
CORPORATION, Tokyo (JP)

() Term: 15 Years

(21) Appl. No.: 35/513,084

(22) Filed: Jun. 7, 2021

(80) Hague Agreement Data

Int. Filing Date: Jun. 7, 2021

Int. Reg. No.: DM/214995

Int. Reg. Date: Jun. 7, 2021

Int. Reg. Pub. Date: Dec. 10, 2021

(51) LOC (14) Cl. 14-01

(52) U.S. Cl.

USPC D21/333; D14/401

CLAIM

The ornamental design for a video game controller, as shown and described.

DESCRIPTION

1. Video game controller

1.1 : Top

1.2 : Bottom

1.3 : Front

1.4 : Back

1.5 : Right

1.6 : Left

1.7 : Perspective

1.8 : Perspective

1.9 : Top

1.10 : Bottom

1.11 : Front

1.12 : Back

1.13 : Right

1.14 : Left

1.15 : Perspective

1.16 : Perspective

1.17 : Perspective

1.18 : Perspective

1.19 : Reference View

1.20 : Reference View

Reproductions 1.1 to 1.8 show the subject design in a shortened state; reproductions 1.9 to 1.16 show the subject design in a lengthened state; reproductions 1.17 and 1.18 show the subject design in a halfway state to lengthened state; reproductions 1.19 and 1.20 are reference views of a state in use a lengthened state; the video game screen unit shown in the reproduction No. 1.19 and 1.20 forms no part of the claimed design.

1 Claim, 20 Drawing Sheets
